(57) **CLAIM**

The ornamental design of a multifunction control unit, as shown and described.

DESCRIPTION

FIG. 1 is a front perspective view of multifunction control unit, showing our new design;

FIG. 2 is a rear perspective view of the multifunction control unit of FIG. 1;

FIG. 3 is a rear elevated view of the multifunction control unit of FIG. 1;

FIG. 4 is a top elevated view of the multifunction control unit of FIG. 1;

FIG. 5 is a bottom elevated view of the multifunction control unit of FIG. 1;

FIG. 6 is a left side elevated view of the multifunction control unit of FIG. 1; and,

FIG. 7 is a right side elevated view of the multifunction control unit of FIG. 1.

The broken lines in the drawings depict features that form no part of the claimed design.
